(57) **CLAIM**

The ornamental design for a door support component, as shown and described.

DESCRIPTION

FIG. 1 is a front isometric view of a door support component showing our new design.

FIG. 2 is a front elevation view thereof.

FIG. 3 is a rear elevation view thereof.

FIG. 4 is a left side elevation view thereof.

FIG. 5 is a right side elevation view thereof.

FIG. 6 is a top plan view thereof; and,

FIG. 7 is a bottom plan view thereof.

The appearance of any portion of the door support component shown within broken lines forms no part of the claimed design.
